UNITED STATES PATENT OFFICE.

THURE A. JOHNSON, OF LYNN, MASSACHUSETTS.

HOLDER FOR SHELVES.

1,347,464.

Specification of Letters Patent.

Patented July 20, 1920.

Application filed August 28, 1919. Serial No. 320,478.

To all whom it may concern:

Be it known that I, THURE A. JOHNSON, a citizen of the United States, and resident of Lynn, county of Essex, State of Massachusetts, have invented an Improvement in Holders for Shelves, of which the following description, in connection with the accompanying drawing, is a specification, like characters on the drawing representing like parts.

This invention relates to improvements in holders for shelves such as ironing boards and the like and the principal object thereof is to provide a convenient means which can be secured to a supporting base such as the top of a table or to a wall and which will serve properly to support the end of the shelf or ironing board so that the main portion or body thereof may project beyond the supporting means.

More specifically the object of the invention is to provide a convenient holder for ironing boards which may be clamped to the top of an ordinary kitchen table and which will support the ironing board at such a distance above the table as to be conveniently in reach of the user.

In such case the space between the ironing board and the table enables the work to be properly manipulated about the ironing board while all portions of the work except that part lying upon the ironing board are supported by the table itself.

Another object of the invention is to provide an ironing board support of the character specified in which the supporting means may be conveniently folded into small compass.

A further object of the invention is to provide an ironing board and an ironing board support which may be conveniently dismantled and the holder for the ironing board folded up into sufficiently compact form to be inserted into a traveler's trunk.

Further objects and features of the invention will more fully appear from the following description and the accompanying drawing and will be pointed out in the annexed claims.

A preferred embodiment of my invention is illustrated in the drawing, in which,

Figure 1 is a perspective view of a portion of the top and legs of a table with an ironing board and ironing board holder embodying my invention supported thereupon,

Fig. 2 is a plan view on a smaller scale

of a preferred form of ironing board, the illustration being of a small size adapted to be packed within a trunk,

Fig. 3 is a side elevation of one of the preferred forms of holders illustrated in Fig. 1, showing the supporting means for the ironing board or shelf in folded position,

Fig. 4 is a plan view of the ironing board holder showing the support in extended position adapted to support the ironing board,

Fig. 5 is a detail view on a larger scale showing a portion of the table top in section with the ironing board holder clamped thereto and the supporting means in operative position, and,

Fig. 6 is a vertical sectional view of the bottom portion of one of the legs of the ironing board holder stand and the table top showing a different form of locking means for securing the stand to the table top.

The invention is disclosed herein as applied to the top 1, of a usual form of kitchen table but it will be understood that the holder may be secured to any suitable base or wall from which it is desired to support an ironing board or other form of shelf.

The holder comprises a stand preferably having a pair of parallel supporting legs 2 and 3 connected by a suitable cross piece which desirably is secured to the top of said legs. The cross piece 4 may be broader than the width of the legs to present an overhanging extension 5 adapted to give a wider area for engaging the top of the shelf or ironing board. A jointed supporting member of greater length than the distance between said legs is preferably pivotally secured to one of said legs.

As illustrated herein the supporting member comprises a board or plate 6 which is secured to the leg 3 by one or preferably a pair of hinges 7. The free end of the member 6 is secured by a hinge 8 to another board or plate 9 of equal width. The length of the members 6 and 9 is such that when folded together they will fit between the legs 2, 3 of the stand thereby making a collapsed construction.

The upper edges of the boards or plates 6 and 9 are spaced apart from the cross piece 4 a sufficient distance to provide for the insertion of the end of an ironing board or other shelf. When the supporting members

6, 9 are in the extended position illustrated in Fig. 1 the lower face of the ironing board or shelf rests upon the upper edges of said supporting members while the lower edges of 5 the supporting members rest upon the top of the table.

The ironing board or shelf therefore is supported from beneath near one end while its more extreme end portion is held down by 10 the cross piece 4. By reason of this construction the lever portion of the ironing board is allowed to project beyond the apex formed by the members 6 and 9 so that the space beneath said ironing board or shelf 15 is free.

Any suitable means may be provided for locking the supporting members in extended or collapsed position. As illustrated herein a hook 10 is pivotally connected to the leg 2 20 and is adapted to engage any one of a series of eyes 11 12 projecting from the side of the board 9 so that a greater or less free space may be provided beneath the ironing board by adjustment of the position of the 25 supporting members.

Another eye 13 is secured to the supporting member 6 in such position as to lock the supporting members in the collapsed position illustrated in Fig. 4 so that they are retained within the area between the supporting legs 2, 3.

Any suitable means may be provided for securing the legs of the stand to a table top or other base. In the preferred embodiment disclosed herein the legs are provided with transverse slots 14 of sufficient width to receive the edge of the table top, suitable fastening means being provided for clamping the legs upon the table top.

40 As illustrated in Fig. 3 the clamping means comprise screws 15 seated in the lower portion 16 of the legs beneath the slot 14. In Fig. 5 a fastening means is illustrated comprising a follower 17 having a 45 pivotally mounted cam 18 secured to the side of said legs, the cam 18 being provided with a lever 19 by means of which it may be oscillated upon its pivot and caused to force the follower into clamping engagement with the table top 1. In the construction illustrated in Fig. 6 the lower end of the legs 2, 3 are provided with slots 20 located just below the recesses 14 and at right angles thereto. A wedge shaped member 21 seated in this slot 55 serves when driven in to clamp the leg 2 firmly upon the edge of the table while a second wedge 22 extending through an aperture 23 in the wedge 21 serves when driven in to perform the double function of driving the wedge 21 tightly in place and also locking the leg 2 against the edge of the table leg.

Various other means may be provided for 60 securing the legs of the stand to the table or 65 other supporting base.

It will be understood that the embodiment of the invention disclosed herein is illustrative merely and is not restrictive and that various modifications may be made within the spirit and scope of my invention; that 70 the supporting device may be used to sustain any form of shelf or other article either temporarily or permanently and that means may be provided for securing the stand either to a horizontal edge such as a table or 75 vertical wall, etc. A desirable form of shelf or ironing board which may be employed in connection with my invention comprises a body portion 24 having a rounded end 25 preferably conforming in contour to the 80 usual coat collar merging into a broadened central portion 26 so that the body of the board conforms substantially to the form of a skirt, and an end portion 27, the edges of which are parallel and adapted to be inserted beneath the cross piece 3.

The device may be of any convenient size such for example as that required to support the usual ironing board or the device may be of sufficiently small size to be conveniently 90 packed away in a trunk together with a smaller ironing board for traveler's use. An ironing board holder of this kind may conveniently be used by the occupants of flats or rooms in which there is a restricted space 95 since the ironing board can be quickly removed and the supporting means collapsed and packed away in a small closet or trunk.

Various other uses of the invention may of course be made within the meaning and 100 scope of the following claims.

Having thus described my invention what I claim as new and desire to secure by Letters Patent, is:

1. A holder for shelves and the like, comprising a stand, means pivotally secured thereto adapted to support a shelf from beneath and means on said stand positioned to engage the shelf from above and hold the same down upon the supporting means. 105

2. A holder for shelves and the like comprising a stand, means for securing said stand to a base, means movably connected to said stand adapted to rest upon said base and to support a shelf from beneath and means on said stand positioned to engage the shelf from above and hold the same down upon said supporting means. 115

3. A holder for shelves and the like comprising a stand, means for securing said stand to a table top, a foldable member pivotally connected to said stand adapted to rest upon said base and to support the shelf from beneath and means upon said stand positioned to engage the shelf from above and hold the same down upon said supporting means. 120

4. A holder for shelves and the like comprising a stand having a plurality of legs and a cross piece connecting said legs, means 130

- for securing said stand to a table top, means pivotally connected to one of said legs adapted to support the shelf from beneath, the upper edge of said pivoted member being spaced apart from the cross piece sufficiently to enable the end of the shelf to be inserted therebetween.
- 5 5. A holder for ironing boards comprising a stand having a pair of legs connected by a cross piece, a table supporting member consisting of two parts hinged together pivotally connected to one of said legs and adapted to be folded between them, the bottom edge of said supporting member being
- 10 15 adapted to rest upon the base and the upper edge of said supporting member spaced apart from said cross piece sufficiently to permit the insertion of the end of the shelf therebetween.
- 20 6. A holder for ironing boards comprising a stand having a pair of legs connected by a cross piece, a table supporting member consisting of two parts hinged together pivotally connected to one of said legs and
- 25 adapted to be folded between them, the bottom edge of said supporting member being adapted to rest upon the base and the upper edge of said supporting member spaced apart from said cross piece sufficiently to
- 30 permit the insertion of the end of the shelf therebetween and means for detachably connecting the free end of said supporting member to the other leg of said stand.
- 35 7. A holder for ironing boards comprising a stand having a pair of legs connected by a cross piece, a table supporting member consisting of two parts hinged together pivotally connected to one of said legs and adapted to be folded between them, the bottom edge of said supporting member being
- 40

adapted to rest upon the base and the upper edge of said supporting member spaced apart from said cross piece sufficiently to permit the insertion of the end of the shelf therebetween, locking means comprising a member secured to the other leg of said stand and coöperating locking means upon said supporting member capable of locking the supporting member alternately in supporting position or in folded position.

8. A holder for ironing boards comprising a stand having a pair of vertical legs and a connecting cross piece, means for securing said stand to a table supporting means consisting of a jointed frame which when extended is of greater length than the distance between said supporting legs but when collapsed will lie between said legs, the upper edge of said supporting means being spaced apart from said cross piece a sufficient distance to permit the end of the ironing board to be inserted therebetween.

9. An ironing board support comprising a stand having a pair of legs provided with recesses adjacent their lower ends adapted to receive the edge of a table top, a cross piece connecting said legs, jointed supporting members of greater length when extended than the distance between said legs pivotally connected at one end to one of said legs and means for detachably securing the other end of said pivotal member to the other leg, the upper edge of said supporting member being spaced apart from said cross piece sufficiently to permit the insertion of the end of an ironing board therebetween.

In testimony whereof I have signed my name to this specification.

THURE A. JOHNSON.
